UNITED STATES PATENT OFFICE.

JOHN ROBERT HINTON, OF PETERSBURG, VIRGINIA, ASSIGNOR TO MASON ROMAINE AND ORLANDO G. HINTON, OF SAME PLACE.

FIRE-CRACKER.

SPECIFICATION forming part of Letters Patent No. 619,177, dated February 7, 1899.

Application filed November 26, 1898. Serial No. 697,545. (No model.)

To all whom it may concern:

Be it known that I, JOHN ROBERT HINTON, a citizen of the United States, residing at Petersburg, in the county of Dinwiddie and State of Virginia, have invented new and useful Improvements in Fire-Crackers, of which the following is a specification.

The improvement which forms the subject of this patent is directed to provisions whereby what is known as the "cannon-cracker" is rendered safe and certain in its use and more attractive as a pyrotechnic.

It is of frequent occurrence in firing the cannon-cracker as a pyrotechnic that the fuse fails to quickly ignite the powder charge or that the fuse only partially burns and apparently goes out, but retains fire likely at any instant to ignite the powder charge. In such cases accidents have happened from handling it and in going near it by reason of its unexpected explosion.

It is the purpose of my improvement to provide cannon-crackers with means whereby they are caused to give certain evidence that the fuse has gone out and that there can be no explosion except it is preceded by a harmless combustion giving a loud whistling sound produced by a chemical composition, thereby rendering the use of a pyrotechnic dangerous for men harmless for children.

The provision of a combustible whistling device to a cannon-cracker involves a construction in which such device, which contains the chemical composition, projects into space in the chamber containing the cannon charge, which only partially fills the cannon-chamber, and as this whistling compound constitutes a fuse for igniting the cannon charge it is important that provision be made for certainly and quickly igniting the whistling compound and for causing it as certainly to ignite the cannon charge. In these particulars my improvement will be specifically set out in the concluding claims, in connection with the accompanying drawings, which illustrate what I term a "whistling cannon-cracker," and in which—

Figure 1 shows in longitudinal section my improved whistling cannon-cracker wherein the device containing the combustible whistling compound is shown as projecting into

the cannon-chamber space. Fig. 2 is a cross-section taken at the plug in which the combustible whistling device is seated. Fig. 3 is a like section showing the combustible whistling device projecting into space in the cannon-chamber; and Fig. 4 shows the whistling device, in which the combustible whistling compound is at its junction with the firing-fuse combined with an initial igniting powder charge and a terminal igniting powder charge for igniting the cannon charge.

The cannon-body is preferably formed of paper suitable for the purpose in cemented wrappings, producing a hollow cylindrical body of strong walls, within which a chamber for containing the cannon charge of powder is formed by a plug 2 of suitable material at or near one end and a plug 3 of fire-clay near the firing end. In this clay plug is centrally seated the whistling device, which consists of a tube 4, formed of hard paper wrappings cemented together, open at both ends, of less diameter than the powder-containing chamber, and seated so as to stand entirely within the firing end of said chamber. This tube contains the combustible whistling compound, (indicated by the numeral 5,) which when fired burns with a loud whistling noise and emits a volume of both smoke and flame. For this purpose the chamber containing this chemical compound is comparatively small and the compound must be tamped solidly within it. The whistling compound in its ingredients, proportions, and mode of manufacture is described in the patent of Antonio Del Grande, No. 411,714, dated September 24, 1889, and the process of producing which consists in dissolving picric acid in hot water, adding carbonate of magnesia thereto to form a solution of picrate of magnesia, then dissolving nitrate of potash in water, and mingling the latter solution with the former, producing a precipitate consisting of picrate of potash, and finally reducing said precipitate to a granular or condition of powder in which it is used as stated; but it will be understood that any suitable chemical composition may be employed so long as it has the capacity when ignited of producing the results stated. This combustible whistling compound does not fill the tube to its ends, but a space is left

at each end, within which a small quantity of fine black powder is tamped in a wet condition, so as to form thin end plugs 6 and 7, to bind and hold solidly against the ends of 5 the chemical whistling composition, thus supplementing a combustible whistling compound made solid in a long body with a comparatively thin layer of powder, which at one end forms an igniting medium 6 for this 10 whistling compound and at the other end of the compound forms an igniting medium 7 for the cannon-cracker charge.

The whistling composition is fired by a fuse 8, which is seen as seated and confined partially within, but preferably does not pass through, the powder layer 6, and is preferably secured by cementing to a paper wrapper cemented to the end of the tube. The fuse may, however, be otherwise secured to the end of 20 the tube so long as its end is in contact with or is surrounded by a layer of powder of sufficient thickness to certainly and instantly communicate by a flash the fire of the fuse to the joining end of the combustible whistling compound. The powder layer at the inner end of the whistling-tube on being fired by the burning of the whistling compound ignites by a flash or by sparks the powder loosely contained in the chamber of the can- 25 non-cracker.

It is important to note that the whistling-tube extends within the cannon-chamber, free of contact with its walls, a sufficient distance to render certain the delivery of and diffusion 35 of the flash or sparks to ignite the charge contained, because by reason of the rapid movement of the fire in consuming the whistling compound the effect of the contact of the fire with the powder layer abutting the com- 40 pound will be to project the powder layer from the end of the tube in sparks into the powder charge of the cannon-cracker.

The powder used for the cannon charge and for the igniter layers of the whistling device 45 is very fine and, as shown in Fig. 3, only partially fills the cannon-chamber, and it is by reason of the partial filling of the chamber that the force of the explosion is increased, and the advantage of combining a terminal 50 powder-igniter layer with the whistling-tube is apparent.

The projection of the whistling-tube into the cannon-chamber places its firing end practically over the powder charge, increases the 55 duration of the whistling sound, and forms an ejector for sparks into the chamber charge. This is one of the features of my improvement, and it is obvious that the whistling-tube so projecting may be used in the cannon-cracker 60 without the powder layers, which supplement the whistling composition.

Another important feature of my improvement is the closure of the whistling-tube entirely within the chamber formed by the cylindrical body, whereby said tube is protected 65 at its fuse-connected end from liability to be broken from its seat connection in the charge-

containing chamber, and particularly as such seat is formed of a clay plug.

I claim as my improvement—

1. In a cannon-cracker, the combination with the chambered body closed by end plugs and partially filled with powder, of a tube open at both ends, of less diameter than said chamber, seated centrally in one of said plugs, 75 extending therefrom into said chamber, and containing a composition capable of emitting a large volume of smoke and flame with a loud shrill whistling sound.

2. In a cannon-cracker, the combination with the chambered body closed by end plugs, and partially filled with powder, of a tube open at both ends, of less diameter than the chamber, entirely inclosed by it, centrally seated in one of said plugs, extending into 85 the chamber and outward from said plug, and containing a combustible whistling composition and an igniting-fuse at its firing end.

3. In a cannon-cracker, and in combination with the chambered body thereof partially 90 filled with powder, of a tube supported centrally in a plug closing one end of said chamber, said tube being of less diameter than the chamber, open at both ends, extending into the chamber and outward from said plug, 95 containing a combustible whistling composition, an igniting-fuse at its firing end and having a layer of powder between the end of the firing-fuse and the end of said composition.

4. In a cannon-cracker, and in combination with the chambered body thereof partially filled with powder, of a tube of less diameter than the chamber, supported centrally in a plug closing one end of said chamber, said tube being open at both ends, extending into 105 the chamber and outward from said plug, containing a combustible whistling composition, an igniting-fuse at its firing end and having a layer of powder in its end opening 110 into the chamber and abutting the end of the whistling composition.

5. In a cannon-cracker, and in combination with the chambered body thereof partially filled with powder, of a tube of less diameter than the chamber, supported centrally in a 115 plug closing one end of said chamber, said tube extending into the chamber and outward from said plug, containing a combustible whistling composition, an igniting-fuse at its firing end and having a layer of powder between the 120 end of the fuse and the end of said composition and a layer of powder in its end opening into the chamber and abutting the end of the whistling composition.

6. In a cannon-cracker and in combination 125 with the chambered body thereof partially filled with powder, of a tube of less diameter than the chamber, supported centrally in a plug closing one end of said chamber, extending into the chamber and outward from said 130 plug, containing a combustible whistling composition supplemented at its firing end by a layer of powder and having the igniting-fuse embedded in the layer of powder.

7. In a cannon-cracker and in combination with the chambered body thereof partially filled with powder, of a tube centrally seated within the end of said chamber, opening into it, containing a combustible whistling composition supplemented at each end of the tube with a layer of powder, and an igniting-fuse in contact with the layer of powder at the firing end of said fuse.
10. 8. A whistling-fuse device for cannon-crackers consisting of a tube open at both ends containing a combustible whistling com-

position, an igniting-fuse at one end, a layer of powder between the end of the fuse and the end of said composition and a layer of 15 powder in its other end abutting the end of said composition.

In testimony whereof I hereunto sign this specification this 22d day of November, 1898.

JOHN ROBERT HINTON.
